UNITED STATES PATENT OFFICE.

FRANK B. WENTWORTH AND LOUIS F. CLAUSING, OF LOS ANGELES, CALIFORNIA.

RADIATOR.

1,247,917.

Specification of Letters Patent. Patented Nov. 27, 1917.

Application filed May 5, 1915. Serial No. 25,958.

To all whom it may concern:

Be it known that we, FRANK B. WENTWORTH and LOUIS F. CLAUSING, both citizens of the United States, residing at Los Angeles, in the county of Los Angeles and State of California, have invented a new and useful Radiator, of which the following is a specification.

This invention relates to radiators for use 10 in connection with internal combustion engines and to improvements in radiators of the type embodied in our U. S. Patent No. 1,188,819, of May 11, 1915, filed January 12, 1914. The primary object of the invention 15 is to provide a simple and economical radiator construction which will provide large size water tubes and a great amount of radiating surface in a comparatively small space, the parts of the radiator being constructed to effectively interlock when assembled 20 so as to enable an expeditious fastening of the parts and provide a strong durable yet flexible construction.

Another object of importance is to provide 25 a radiator which comprises tube units between which are interposed spacer plates which interlock with the units, and provide large air channels which are transverse to the tube units, said units being grooved 30 transversely to receive the spacer plates, which plates are corrugated and the corrugations engage in the grooves.

The invention consists in certain novel 35 features of construction and combinations, and arrangement of parts as will be more fully hereinafter described and pointed out in the claims.

Referring to the drawings:

Figure 1 is a fragmentary plan view of 40 our improved radiator construction;

Fig. 2 is a vertical sectional view taken on line 2—2, of Fig. 1;

Fig. 3 is a horizontal sectional view taken on line 3—3, of Fig. 2;

Fig. 4 is a perspective view of one of the spacer plates;

Fig. 5 is a fragmentary inside plan view 45 of the tube plate;

Fig. 6 is a fragmentary top plan view of 50 the modified form of radiator construction;

Fig. 7 is a fragmentary top plan view of one of the spacer plates of the modified 55 form of radiator;

Fig. 8 is a side elevation partly in section 60 of the modified form;

Fig. 9 is a horizontal sectional view taken on line 9—9, of Fig. 6; and

Fig. 10 is a fragmentary inside elevation of one of the tube plates of the modified form.

In the present embodiment of the invention, tube plates 1 arranged in pairs to provide water tubes, and spacer plates 2, arranged between the pairs of tube plates to provide transverse air channels are used.

The tube plates are identical as to construction and each has a plurality of transverse substantially V-shaped corrugations 3 thereon. The inner face of each of the tube plates is flattened on the crests of the corrugations 3 at points between the ends of the corrugations, as at 4. From points near but spaced from the ends of the unflattened portions of the crests of the corrugations 3, the unflattened portions are inclined or tapered 75 toward the flattened portions 4. This is done to give as much width and capacity as possible to the tubes formed by the plates.

The tube plates are nested together so that the convex portions of one plate register with the concave portions of the other plate and are then secured to one another along their longitudinal edges, preferably by soldering.

The spacer plates 2 illustrated in Fig. 4 85 is simply a transverse corrugated plate in which the corrugations are preferably substantially V-shaped. In order to provide for the interlocking of the spacer plates with the opposed tube plates between the 90 tubes, as shown in Fig. 2 in the drawings, the outer face of each of the tube plates is provided with longitudinal preferably substantially V-shaped grooves 5 which are formed in the crests of the corrugations intermediate the ends of said crests. The end portions of the crests which are free of the grooves are located in the same plane as are the bottoms of the grooves in order that the crests of the corrugated spacer plates 2 will 100 engage with the crests of the plates 1 throughout the entire length of the corrugations. The crests of the spacer plate in interlocking with the grooved crests on the outer faces of the tube plates prevent longitudinal shifting of the plates relative to one another and insure a perfect soldering at the engaging points of the tube and spacer plates.

Fig. 2 in the drawings, represents a sec-

tion of a radiator constructed in accordance with our invention and illustrates a number of tube units between which are arranged spacer plates. As shown in Fig. 2, the water tubes A are of a tortuous nature and provide a maximum radiating surface. In view of the interlocking of the tube and spacer plates, the metal is given a chance to bend between the joints where it is soldered without causing leakage at the joints. The space plates provide comparatively large air passages B which are transverse to the tubes A and are of irregular contour internally, thus causing the air to contact all of the opposed metal faces of the tube plates.

Referring to Figs. 6, 7, 8, 9 and 10 wherein we have illustrated a modified form of radiator construction, the tube and spacer plates 6 and 7 are constructed so that the lateral air passages are hexagonal in cross section instead of diamond shape as in the preferred form.

The tube plates have a plurality of transverse corrugations 8 thereon. The inner faces of the tube plates 6 are flattened on the crests of the corrugations throughout the entire length thereof. Centrally of the ends of the flattened crests of the corrugations, the crests are inwardly offset as at 9. The inwardly offset flattened portion 9 of each corrugation 8 terminates at its ends in inclined or tapered flat portions 10 which communicate with the flattened end portions 11 of the crests, said end portions 11 being located in the same plane and are the engaging points of each pair of tube plates. The plates in the modified form are nested together as in the preferred form with the flattened faces 9 opposed and engage one another at the flattened ends 11 of the corrugations, the portions 9 and 10 of the corrugations providing substantially wide tortuous passages or water channels. The plates are soldered at the ends 11 where they engage with one another and perfect joints are provided. On the outer faces of the plates 6 in the crests of the corrugations are formed substantially V-shaped grooves 12 which terminate near the ends of the crests in flat end portions 13, said portions 13 being located in the same plane as the bottom of the grooves 12.

The spacer plates 7 have a series of transverse corrugations 14, each of which has a substantially V-shaped crest portion 15 formed intermediate its ends and which terminates at the ends of the corrugations in flattened end portions 16 corresponding to the portions 13 on the tube plates 6 and adapted to engage said portions 13. After the tube plates have been assembled in pairs as heretofore described, the substantially V-shaped crest portions 15 are positioned within the grooves 12 and the portions 16 of the spacer plates 7 engage the flat end portions

18 of the tube plates, as shown clearly in Fig. 9 in the drawings. With the spacer plates interlocked in the hereinbefore described manner, with the tube plates, slipping of the spacer plates relative to the tube plates is prevented and the soldering of the plates to one another may be had in an expeditious and reliable manner.

The hereinbefore described modified form is similar to the preferred form relative to the water and air passages. The air passages in the modified form are hexagonal and the water passages are tortuous as in the preferred form.

What we consider the most important feature of our improved radiator is the interlocking arrangement between the spacer and tube plates. This arrangement gives a greater flexibility of parts since it permits the metal to be bent without affecting the joints or causing the plates to shift appreciably relative to one another.

In practice we have found that the form of our invention illustrated in the drawings and referred to in the above description as the preferred embodiment is the most efficient and practical, yet realizing that the conditions concurrent with the adoption of our device will necessarily vary, we desire to emphasize the fact that various minor changes in construction, proportion and arrangement of parts may be resorted to when required without sacrificing any of the advantages of our invention as set forth in the appended claims.

We claim:

1. In a radiator, the combination with spaced tube units having transverse grooves formed in spaced parallel relation to each other in the opposed outer faces thereof, said grooves terminating at points spaced from the vertical edges of the tube units and having their bottoms in the same plane as the ungrooved portions of the tube units, and a spacer plate having corrugations therein secured to and between the tube units with its corrugations engaged within the grooves and upon said ungrooved portions.

2. A radiator comprising a plurality of tube units each having grooves in the outer faces thereof and a corrugated spacer plate secured to and between the units, the crests of the corrugations of the spacer plate being flattened at their ends and the unflattened portions of the crests engaging in the grooves, said tube units having flattened portions engaged by the flattened portions of the spacer plates, said flattened portions of the tube units being located at the ends of the grooves therein.

3. In a radiator the combination with water tube units having transverse corrugations in their opposed outer faces and grooves in the crests of the corrugations terminating at points slightly spaced from the

ends of said crests, said ungrooved ends of the crests being located in the same plane as the bottoms of the grooves, and a spacer plate having corrugations therein secured to and between the tube units with its corrugations engaged in the grooves and with the ungrooved portions of the corrugations of the tube units.

4. In a radiator the combination with spaced parallel water tube units having transverse corrugations in their opposed faces, said corrugations being spaced from one another and provided with grooves terminating at points slightly spaced from the ends of the crests of the corrugations, said ungrooved ends of the crests of the corrugations being in the same plane as the bottoms of the grooves, said grooves being substantially V-shaped, and a spacer plate having corrugations of substantially V-shape therein secured to and between the units with the crests of its corrugations engaged in the grooves.

5. In a radiator, the combination, with spaced tube units having corrugated opposed outer faces provided with grooves formed in and intermediate the ends of the corrugations, of a spacer plate having corrugations therein with the crests of the corrugations of the spacer plate engaged in the grooves in the tube units, said grooves in the tube units having their bottoms in the same plane as the ungrooved portions of the corrugations of the tube units whereby the crests of the corrugations of the spacer plate will engage with the corrugations of the tube units throughout the lengths thereof.

In testimony whereof, we have hereunto set our hands at Los Angeles, California, this 29th day of April, 1915.

FRANK B. WENTWORTH.
LOUIS F. CLAUSING.
